UNITED STATES PATENT OFFICE.

EDWARD W. DAVENPORT AND HENRY BARDSLEY, OF PROVIDENCE, RHODE ISLAND, ASSIGNORS TO CROMPTON & KNOWLES LOOM WORKS, OF PROVIDENCE, RHODE ISLAND, A CORPORATION OF RHODE ISLAND.

LOOM-SHUTTLE.

SPECIFICATION forming part of Letters Patent No. 691,607, dated January 21, 1902.

Application filed September 25, 1901. Serial No. 76,462. (No model.)

To all whom it may concern:

Be it known that we, EDWARD W. DAVENPORT and HENRY BARDSLEY, citizens of the United States, residing at Providence, in the county of Providence, State of Rhode Island, have invented a certain new and useful Improvement in Loom-Shuttles, of which the following is a specification, reference being had therein to the accompanying drawings.

10 The invention relates to the devices which are employed in loom-shuttles for the purpose of ascertaining when the yarn-load which is carried by the working shuttle of a loom has become exhausted or depleted to the predetermined extent and for the further purpose of calling into action instrumentalities for bringing about a prearranged change in the working of the loom.

15 The invention consists in improved devices of the said class, and first will be described with reference to the drawings, in which latter is represented an embodiment of the invention, after which the characteristic and essential features thereof will be particularly 20 pointed out, and distinctly defined in the claims at the close of this specification.

25 In the drawings, Figure 1 shows, mainly in horizontal section, a portion of a loom-shuttle having the said embodiment of the invention applied thereto. Fig. 2 shows the same, mainly in vertical section. Fig. 3 shows the same in transverse vertical section on the plane indicated by the dotted line 3 3, Fig. 1.

Having reference to the drawings, 1 designates the body of a loom-shuttle.

2 is a shuttle-spindle pivoted within the shuttle-body upon a transverse pin 3, as usual.

4 is the usual spindle-actuating spring, 30 making contact with the head of the spindle 2.

5 is a bobbin-catch applied to the heel 21 of the spindle, as customary, and 6 is the disengaging pin by means of which the bobbin-catch 5 is held back when the tip of the spindle 45 is raised, thereby disengaging the said bobbin-catch from the groove 71 in the head of the bobbin 7, mounted upon the spindle.

In general the foregoing parts are or may be as heretofore or as preferred.

In conformity with our invention we apply 50 to the shuttle-spindle 2 a movable feeler, which is operated through the agency of a spring tending to move the feeler transversely of the spindle. In applying a yard-load to the shuttle-spindle the said yarn-load is 55 caused to inclose or surround the feeler. By means of the yarn-load, which is placed exterior to the spindle and feeler, so as to surround them, the said feeler is confined in an abnormal position. So soon, however, as the 60 said yarn-load becomes unwound and drawn off in the operation of weaving sufficiently far to leave the feeler free to move, the said feeler is operated by a spring and caused to assume its normal or operative position. It 65 is intended that the said feeler in the normal or operative position thereof shall coact with or control outside instrumentalities for bringing about the desired results in the working of the loom in which a shuttle embodying the 70 invention is employed. Thus, as will be obvious to those who are skilled in the art, the said feeler may be utilized to bring about an arrest of the action of the whole or some part of the loom mechanism or to bring about automatic replenishment of the working weft-supply, all substantially as heretofore proposed in the art. The said outside instrumentalities and the precise manner of the co-operation of the trip therewith are not mate- 75 rial to our invention, which resides more especially in the shuttle and its parts. The construction and arrangement of the feeler and coacting parts may vary somewhat in practice. 80

85 A movable feeler, such as that which is referred to above, is shown at 8. It is shown connected with the shuttle-spindle 2 by means of a pivot-pin 9, arranged near the inner end of the feeler. The feeler swings radially with respect to the shuttle-spindle upon said pivot-pin. Preferably, although not necessarily, in all embodiments of the invention the feeler is mounted in position to swing transversely

of the shuttle, as shown. Preferably, also, the shuttle-spindle is formed with a slot 21^a, extending longitudinally thereof, within which slot the feeler is fitted and works. 5 Thereby the feeler is protected or shielded and steadied in its working. When a yarn-load is applied to the shuttle-spindle, whether such yarn-load is contained upon a bobbin or not, the working arm of the feeler is inserted 10 into the central opening of said yarn-load together with the shuttle-spindle. For the purpose of causing the working arm of the pivoted feeler to press outwardly against the portion of the yarn-load which surrounds the 15 same a spring-actuated presser or plunger is caused to act against the inner portion of the feeler. The said presser-plunger is arranged to move longitudinally of the shuttle-spindle. Such a presser or plunger is shown at 10. It 20 preferably is contained within a passage formed in the shuttle-spindle and extending longitudinally of the latter. The head of the presser or plunger bears against the cam-shaped edge of the inner arm of the feeler. 25 The actuating-spring 12 occupies the said passage, said spring surrounding the stem of the presser or plunger and being compressed between the rear shoulder of the head of the latter and the inner end of the screw 13. The 30 said screw is fitted to the outer end of the passage 11 and is hollow to receive and guide the stem of the presser or plunger.

For the purpose of automatically closing the working arm of the feeler into line with 35 the shuttle-spindle when the latter is raised, and thereby facilitating the application of a yarn-load to the spindle or the removal of the same from the latter, we provide a closing-cam 14. (See more especially Fig. 3.) The 40 said cam 14 is applied to an interior wall of the shuttle-body adjacent the pivot of the shuttle-spindle and is provided with an acting face which is shaped and arranged, as shown, so that in the depressed and horizontal 45 position of the shuttle-spindle the feeler is free of the cam and subject to the control of its spring - actuated presser or plunger, while as the shuttle-spindle is raised into its outturned position the tail or heel of the feeler 50 is acted upon by the said acting face of the closing-cam 14, and thereby the feeler is swung into line with the axis of the spindle.

In the case of using yarn which is wound 55 upon bobbins each bobbin 7 is formed with a slot 72 through one side thereof, within which the working arm of the feeler may enter and through which slot said arm may swing outwardly into contact with the coils of yarn which are wound upon the exterior of the 60 bobbin. For the purpose of preventing the bobbin from turning upon the shuttle-spindle, so as to cause a wall of the slot 72 to bind against the feeler 8 and impede or prevent the movement thereof, we provide a bobbin-

positioning device 15, constituted by a bent 65 spring-strip having its yielding free extremity provided with a projection 151, which enters the slot 72.

In the case of the illustrated embodiment of our invention it is contemplated that the 70 working arm of the feeler when the feeler is released by the drawing off of the coils of yarn confining the same shall project through a slot 16 in one wall of the shuttle-body, so that its end may engage with the exterior instrumentalities, to which reference is made at the 75 outset hereof.

We claim as our invention—

1. In a loom-shuttle, in combination, the shuttle-body, the shuttle-spindle, the feeler 80 pivotally connected to the shuttle-spindle and adapted to be confined in an abnormal position by a yarn-load exterior to the shuttle-spindle, and the spring-actuated plunger by which said feeler is operated. 85

2. In a loom-shuttle, in combination, the shuttle-body, the slotted shuttle-spindle, the feeler pivotally mounted in the slot of the shuttle-spindle and adapted to be confined in an abnormal position by a yarn-load exterior 90 to the shuttle-spindle, and the spring-actuated presser by which said feeler is operated, movable longitudinally of the shuttle-spindle. 95

3. In a loom-shuttle, in combination, the shuttle-body, the shuttle-spindle having a longitudinal passage, the feeler pivotally connected to the shuttle-spindle and adapted to be confined in an abnormal position by a yarn-load exterior to the shuttle-spindle, and the spring-actuated plunger contained in said longitudinal passage and operating said feeler. 100

4. In a loom-shuttle, in combination, the shuttle-body, the shuttle-spindle, the slotted bobbin, the feeler pivotally connected to the shuttle-spindle and working in the slot of the 105 bobbin, and the spring-actuated presser by which said feeler is operated, movable longitudinally of the shuttle-spindle.

5. In a loom-shuttle, in combination, the shuttle-body, the shuttle-spindle having a longitudinal passage, the feeler pivotally connected to the shuttle-spindle and working in the slot of the bobbin, and the spring-actuated plunger contained in said longitudinal 110 passage and operating said feeler. 115

6. In a loom-shuttle, in combination, the shuttle-body, the slotted shuttle-spindle, the slotted bobbin, the feeler pivoted in the slot of the spindle and working in the slot of the bobbin, and the spring-actuated presser by 120 which said feeler is operated, movable longitudinally of the shuttle-spindle.

7. In a loom-shuttle, in combination, the shuttle-body, the shuttle-spindle, the spring-actuated feeler pivoted to the shuttle-spindle 125 and adapted to be confined in an abnormal position by a yarn-load exterior to the shuttle-spindle, and the closing-cam whereby said

feeler is moved into line with the shuttle-spindle as the latter is elevated.

8. In a loom-shuttle, in combination, the shuttle-body, the shuttle-spindle, the feeler pivoted to the shuttle-spindle and adapted to be confined in an abnormal position by a yarn-load exterior to the shuttle-spindle, the spring-actuated presser or plunger acting against said feeler, and the closing-cam where-

by said feeler is moved into line with the shuttle-spindle as the latter is elevated.

In testimony whereof we affix our signatures in presence of two witnesses.

EDWARD W. DAVENPORT.
HENRY BARDSLEY.
